UNITED STATES PATENT OFFICE.

FRANK COMMINGE, OF PITTSBURG, PENNSYLVANIA.

RESISTANCE-COIL.

SPECIFICATION forming part of Letters Patent No. 668,555, dated February 19, 1901.

Application filed December 11, 1900. Serial No. 39,483. (No model.)

To all whom it may concern:

Be it known that I, FRANK COMMINGE, a citizen of the United States of America, and a resident of Pittsburg, county of Allegheny, 5 State of Pennsylvania, have invented certain new and useful Improvements in Resistance-Coils, of which the following is a specification, reference being had to the accompanying drawings, forming part of this specification, 10 in which—

Figure 1 is a diagrammatic view showing the application to a high-potential current of my improved resistance-coil. Fig. 2 is a perspective view of the device, partly broken 15 away, illustrating the winding. Fig. 3 is a longitudinal section showing the terminal wires. Fig. 4 is a cross-section on the line IV IV of Fig. 3. Fig. 5 is an end view.

My invention relates to means for reducing 20 the voltage of electric currents, whereby I am enabled to utilize currents of high potential for use in electric bells, gongs, annunciators, &c., by which a "light" current of, say, one hundred and ten or fifty-two volts, direct or alternating, may be reduced down to 25 a voltage suitable to the winding of the magnets used in such devices to ring such bells, gongs, annunciators, &c. In devices for this purpose it has been the practice to use fine 30 wire insulated by wrapping and arranged in coils to give the desired results; but such construction is quite expensive, and my invention provides sufficient resistance in suitably-coiled wire by insulating the different 35 layers from each other and properly separating the coils, together with the employment of a suitable surrounding covering or packing, whereby the wires are protected from moisture or from any possible electric contact 40 or danger of short-circuiting.

In the construction of my invention separate series of coils 2 are wrapped around insulating-layers 3 of sheet-asbestos or other suitable insulating material, which should be, 45 preferably, incombustible and a non-conductor of heat, and for this purpose I have found thin sheets of asbestos-paper to be well adapted and suitable for the objects in view.

In the construction of the resistance-coil 50 the innermost sheet is first laid around a mandrel and the first layer of wire 2 is wound around it from one end to the other, leaving

the terminals 4 projecting outwardly at the end where the winding is commenced. After the first layer is thus wound entirely from 55 end to end another layer of asbestos 3 is laid over the first winding and a similar winding is made around its outer surface from the other end back to the starting-point, the wire being continuous, and such operation is con- 60 tinued by adding additional intervening layers 3 and winding over them from one end to the other alternately until the final outer layer is wrapped with the last coil of wire, as shown at the right of Fig. 2, when the wire is 65 led outwardly beyond the end opposite to the starting-point, terminating in terminals 5. The wrapping-wire is preferably comparatively fine wire. The terminals 4 and 5 are considerably heavier sections, providing suit- 70 able connecting-terminals for the terminals of the branch circuit leading from the high-voltage main-current wire. After being so wound the entire resistance is then surround- 75 ed on the inner and outer sides at each end by an inclosing substance 6, as plaster-of-paris, clay, porcelain, glass, or any other suitable fireproof material, which provides an impervious covering for the wire and asbestos layers, and through which at each end the 80 terminal wire projects, and to which attachment can be easily made. It will be observed that the inner wall of the central opening left by the mandrel is also coated, leaving a central open conduit through the middle of the 85 coil through which air may circulate, thus tending to reduce any heat generated in the device by passage of the current. The espe- 90 cial advantage of this outer covering is to provide a positive moisture-proof and fire- 95 proof inclosing substance, whereby the danger of short-circuiting or destruction by heat is entirely prevented. This covering top is cast around the resistance in a plastic condition by means of a suitable mold and when 100 hardened entirely incloses the resistance, as I have described, and presents a neat and finished appearance, leaving the coil in shape for commercial use. If desired, the outside may be painted or varnished with any sub- 100 stance adapted to suitably color it, which also provides an impervious coating, which prevents the entrance of moisture to the interior.

As thus constructed my improved resist-

5 ance may be attached to conductors of high-potential current, and the reduced current may be safely used for any purpose for which the low voltage is peculiarly adapted. By its use I avoid the necessity of batteries of any kind and am able to tap the ordinary electric-light circuit for supplying such low-potential current for any of the various uses for which it may be required.

10 The advantage of this invention will be appreciated by those skilled in the art, as it is much cheaper and simpler and requires no attention whatever after installation, thus rendering it more completely available than the ordinary batteries now in use.

15 Having described my invention, what I claim is—

20 1. A resistance-coil consisting of one or more cylindrical layers of insulating material, wound around with conducting-wire terminating in attaching-terminals, with a surrounding covering of an impervious substance, substantially as set forth.

25 2. A resistance-coil consisting of a plurality of cylindrical layers of insulating material, a central longitudinal air-passage therethrough, a conducting-wire wound around each layer successively, alternately from one end to the other whereby the successive wrappings of the wire are insulated from each

other, terminating in attaching-terminals, substantially as set forth.

30 3. A resistance-coil consisting of a plurality of cylindrical layers of insulating material, a conducting-wire wound around each layer successively, alternately from one end to the other, whereby the successive wrappings of the wire are insulated from each other, terminating in attaching-terminals, and a surrounding covering of impervious substance 35 through which the terminals extend, substantially as set forth.

40 4. A resistance-coil consisting of a plurality of cylindrical layers of insulating material, a conducting-wire wound around each layer successively, alternately from one side to the other, whereby the successive wrappings of the wire are insulated from each other, terminating in attaching-terminals, and a surrounding covering of impervious substance 45 50 through which the terminals extend, and an outer coating of impervious substance laid over such substance, substantially as set forth.

Signed at Pittsburg, Pennsylvania, this 3d 55 day of December, 1900.

FRANK COMMINGE.
